UNITED STATES PATENT OFFICE.

JOHN S. S. FULTON, OF CHICAGO, ILLINOIS, ASSIGNOR TO THOMAS BATES, OF TORONTO,
ONTARIO, CANADA.

STOVE-LID.

1,258,760.

Specification of Letters Patent.

Patented Mar. 12, 1918.

Application filed July 19, 1915. Serial No. 40,790.

To all whom it may concern:

Be it known that I, JOHN S. S. FULTON, of the city of Chicago, in the State of Illinois, in the United States of America, formerly of the town of Franklin, in the State of Pennsylvania, have invented a new and useful Improvement in Stove-Lids, of which the following is a specification.

My invention relates to improvements in stove lids. The main object of my invention is to provide a lid through which pre-heated air is distributed over the top of the fire in order to secure a more complete combustion of the gases.

Another object of my invention is to supply a lid made in two pieces, and having an upper side altogether similar in appearance to an ordinary stove lid.

A further object of my invention is to provide a lid by means of which warmed air may be distributed evenly in all directions over the whole fire.

The principle on which my lid operates is the same as that described in my United States Letters Patent No. 711,044, for improvements in locomotive boilers dated October 14th 1902.

My invention consists in the provision of a lid comprising an upper and a lower half held together by rivets or other suitable means. The lower half has a series of internal air passages leading from opposite the poker hole, which preferably forms the inlet, to a central chamber from which small outlets are so arranged that the warmed air is distributed evenly in all directions over the top of the fire.

My invention is more fully described with the aid of the accompanying drawings in which similar parts are similarly described:—

Figure 1 is a plan of the upper face of the lower portion, and

Fig. 2 a section on the line 2—2 of Fig. 1.

Fig. 3 is a plan of the underside of the upper portion, and

Fig. 4 a section on the line 4—4 of Fig. 3.

Fig. 5 is a side elevation of the whole lid.

Referring to the drawings 1 designates the upper portion of the lid which has a recess 2 on its underside against which the rings 3 of the lower portion rest. The poker hole 5 must be arranged over the cavity 6. Communicating passages 7, 8, 9, 10 and 11 lead to the chamber 12 in the boss 13 through which the outlets 14 are arranged. Holes 15

are provided in both the upper and lower portions 1 and 4 so that the said portions may be held together by rivets or other suitable means.

The method of operation of my lid is as follows:—

Air enters through the poker hole 5 into the cavity 6 and passing around the rings 3 in the passages 7, 8, 9, 10 and 11 becomes gradually heated as it reaches the central chamber 12. The air is then drawn down through the outlets 14 over the top of the fire, and distributed substantially evenly in all directions.

If desired any other form of inlet may be employed instead of the poker hole as shown in the accompanying drawings. But for the usual stove the area thereof is ample, and using the poker hole has the added advantage than when desired to damp the fire the end of the poker may be inserted and the desired result obtained.

Having thus described my invention what I claim and desire to secure by Letters Patent is:

1. An air heating stove lid including a plate provided with an inlet opening near its periphery, a facing member secured to the underside of said plate and covering the air inlet opening, a series of concentrically arranged rings integral with said facing member and abutting said plate, said rings each having but a single opening and the opening of each of the successive rings being diametrically opposite the opening in each adjacent ring whereby labyrinth passages are formed leading from said inlet opening to the center of the facing member, and a chamber at the center of said facing member and having one foraminous wall adjacent the fire to direct the heated air downwardly into the fire.

2. An air heating stove lid including a plate provided with an inlet opening near its periphery, a facing member secured to the underside of said plate and covering the air inlet opening, a series of concentrically arranged rings integral with said facing member and abutting said plate, said rings each having but a single opening and the opening of each of the successive rings being diametrically opposite the opening in each adjacent ring whereby labyrinth passages are formed leading from said inlet opening to the center of the facing member, a deflector partition connecting the outside

wall of said facing member with the innermost ring at a point diametrically opposite the opening in the latter to form two labyrinth passages, one on each side of the center line of said facing member and each leading to the center, and a chamber at the center of said facing member and having

one foraminous wall adjacent the fire to direct the heated air downwardly into the fire.

JOHN S. S. FULTON.
